CORE DRILL AND VALVE THEREFOR

Leonard Bradley, Whittier, Calif., assignor to
Howard W. Stepp, Whittier, Calif.

Application July 27, 1932, Serial No. 625,145

1 Claim. (Cl. 255—72)

This invention relates to well drilling tools, and relates more particularly to core drills. It is a general object of the present invention to provide an improved core drill in which is embodied a simple, practical and particularly dependable valve means in connection with the inner barrel or core barrel.

Core drills for obtaining cores or samples of the formation in a well bore usually embody an inner barrel provided at its upper end with a valve. The valve on the upper end of the inner barrel is provided to permit fluid to discharge from the upper end of the inner barrel as the core is being taken, and to prevent the circulation fluid from entering the inner barrel and from washing against the core. The types of core drills in general use embody ball valves on the upper end of the inner barrel consisting of a seat, a ball to cooperate with the seat, and a cage for holding or containing the ball. In the class of valve just mentioned, the opening in the valve seat and the openings in the cage are comparatively small and pieces of débris in the well often become lodged in the cage and valve seat and prevent closing of the valve. When this occurs, the circulation fluid is free to pass down into the inner barrel and to wash against the core and sometimes destroys or partially destroys the core.

An object of the present invention is to provide a core drill involving a novel and improved combination and arrangement of parts and including a particularly effective and dependable valve means on the inner barrel or core barrel.

It is another object of the invention to provide a core drill of the character mentioned including a valve on the inner core receiving barrel that cannot be held open or be rendered inoperative by the presence of débris that might pass upwardly in the barrel.

It is another object of the invention to provide a core drill including a valve on the core barrel that provides an opening of maximum capacity between the valve member and the valve seat when the valve member is in the open position so that there is little or no danger of an object or piece of débris holding the valve open.

It is another object of the invention to provide a core drill of the character mentioned that includes a valve on the upper end of the core receiving barrel having means for straining the fluid that passes upwardly through it.

It is another object of the present invention to provide a valve of the character mentioned

for use on a core barrel that does not include a cage or other structure liable to catch or hold objects that may be capable of holding the valve member in the open position.

It is another object of the invention to provide a valve for use in connection with a core drill in which the valve member is shaped and arranged so that comparatively large objects may pass through the valve and will not hold the valve member in the open position.

A further object of the invention is to provide a valve for use in connection with a core drill that is particularly simple and inexpensive of manufacture.

Further objects and features of the invention will be best and more fully understood from the following detailed description of typical forms and applications of the invention, throughout which description reference will be had to the accompanying drawing, in which:

Fig. 1 is a central longitudinal detailed sectional view of the core barrel provided by the present invention illustrating one embodiment of the valve. Fig. 2 is an enlarged vertical detailed sectional view of the valve with the valve member in elevation. Fig. 3 is a transverse detailed sectional view taken as indicated by line 3—3 on Fig. 2. Fig. 4 is a view similar to Fig. 2 illustrating a modified type of fluid straining means, and Fig. 5 is a transverse sectional view taken substantially as indicated by line 5—5 on Fig. 4.

The core drill illustrated in Fig. 1 of the drawing includes an outer barrel 10, a cutter head 9 on the lower end of the barrel 10, an inner barrel 11, and a valve means 12 on the upper end of the inner barrel.

The outer barrel 10 is adapted to be attached to the lower end of an operating string of drill pipe, or the like. In the particular case illustrated in the drawing, a shouldered connecting member 13 is provided to facilitate connection of the outer barrel 10 with the operating string. A sub or connecting member 14 connects the cutter head 11 with the lower end of the outer barrel 10. The cutter head 9 is provided to make an annular cut in the formation and includes a plurality of cutting blades 15. The cutter head 9 is tubular, having an opening 16 adapted to pass the core formed by the cutters 15 upwardly into the inner barrel 11. The inner barrel 11 is provided to receive and hold the core as the tool is fed downwardly into the formation. The inner barrel or core barrel 11 is arranged within the outer barrel 10 and is connected with the cutter head. The lower end of the inner barrel 11 is screw-

threaded into the upper end of the opening 16 in the cutter head 9. The inner barrel 11 is proportioned so that it is spaced from the inner walls of the outer barrel 10 and the circulation fluid passes downwardly around the inner barrel and discharges from spaced openings 18 in the cutter head 9. A suitable core catcher 19 is arranged within the opening 16, and the cutter head. The core catcher 19 has spring fingers 29 adapted to bite into the core when the tool is raised, to break the core away from the formation and to support the core in the inner barrel 11.

The valve means 12 includes generally, a seat member or body 21 on the upper end of the inner barrel 11, a valve member 22, and means 23 for straining fluid passed upwardly through the body 21.

The seat member or body 21 is a simple integral part attached to the upper end of the core barrel 11. The body 21 is tubular having a central longitudinal opening or fluid passage 24. In accordance with the broader principles of the invention, the body 21 may be attached to the inner barrel 11 in any suitable manner. In the particular case illustrated in the drawing, the body 21 is screw threaded on to the upper end of the barrel 11. The lower end portion of the opening 24 is of substantially the same diameter as the opening in the core barrel 11, and is provided at its upper end with a reduced or restricted portion 25 providing a downwardly facing annular shoulder 27 in the body 21. A valve seat 26 is provided on the upper end of the body 21 to receive or cooperate with the valve member 22. The seat 26 is tapered downwardly and inwardly and is annular surrounding the upper end of the body opening. If desired or found practical, the upper end portion of the body 21 may be of reduced external diameter as illustrated throughout the drawing.

The valve member 22 is adapted to normally cooperate with the seat 26 to prevent the circulation fluid from passing downwardly into the inner barrel 11, and is operable to move upwardly out of engagement with the seat 26 upon fluid within the inner barrel 11 being forced upwardly when the core enters its lower end. The valve member 22 may be a solid integral part of round cross section. A frusto-conical or downwardly and inwardly tapered lower end face 29 is provided on the valve member 22 to cooperate with the seat 26. The valve face 29 is of the same pitch or inclination as the seat 26 so that it is adapted to effectively seal with the seat. The valve face 29 is comparatively long, extending downwardly in the opening 25 for a considerable distance and terminating in a downwardly extending stem 30. In addition to sealing with the seat 26, the valve face 29 is adapted to engage the seat when the valve is in the open position, to permit the valve member 22 to swing, rotate or tilt at will. Due to the taper or inclination of the valve face 29 and the seat 26, the valve member 22 automatically centers itself when moving to the closed position. A cylindrical outwardly projecting shoulder 31 may be provided on the valve 12 immediately above the face 29. The head or upper end portion 32 of the valve member 22 may taper upwardly and inwardly from the shoulder 31 and may terminate in a reduced lug 33. The valve member 22 formed as described above, is of sufficient weight to properly seal with the seat 26, and to automatically center itself on the seat. The

tapered head 32 of the valve member properly sheds or diverts the downwardly flowing circulation fluid passing through the core drill. A concave seat or socket 20 is provided in the upper end of the reduced lug 33. The socket 20 is adapted to receive and center an acid bottle, an inclinometer, or other device lowered through the drilling string.

The means 23 is provided to prevent large objects from passing upwardly into the opening 25 when the core is entering the inner barrel 11 and the valve member 22 is in the open position or is moving to the open position. The means 23 also acts to limit the upward movement of the valve member 22. In accordance with the invention, the means 23 is connected with the valve member 22 and includes a straining member and a stop member 35 attached to the stem 30. In the particular form of the invention being described, the member 35 is in the nature of a 20 perforated or cut out disc and is rigidly attached to the stem 30. The stop member 35 is preferably permanently attached to the lower end of the stem 30. A plurality of equally spaced openings 36 is provided in the stop member 35. The openings 36 extend into the member 35 from its periphery and are comparatively large. In the particular case illustrated in the drawing, there are three openings 36 in the stop member 35 spaced apart so as to provide three like radial arms 37. The outer edges of the arms 37 are adapted to slidably engage the walls of the opening 24 and are tapered or rounded as illustrated in Fig. 2 of the drawing to permit the valve member 22 to tilt and swing at will. The upper faces of the arms 37 are attached to come into engagement with the downwardly facing shoulder 27 to limit the upward movement of the valve member 22. The openings 36 in the stop member 35 are sufficiently large to pass the necessary or desired quantity of fluid, but the arms 37 are shaped and proportioned so as to prevent large objects from passing upwardly into the opening 25.

The stem 30 is formed sufficiently long to permit considerable upward movement of the valve member 22 from its seat 26 so that a space of large capacity is provided between the valve member and the seat when the valve is in the extreme up or open position. Due to this proportioning, objects that may pass through the openings 36 of the stop member are also free to pass outwardly between the valve member 22 and the seat 26. Further, the tapering lower end 29 of the valve and the tapering seat 26 allow the valve member 22 to tilt to various positions and to provide for a maximum opening between the valve member and the seat 26. The lower end portion 29 of the valve is smooth and tapering so that there is no tendency for débris to become caught between it and the valve seat.

During operation of the core drill, circulation fluid is passed downwardly through it under pressure to discharge from the openings 18 in the cutter head. The core drill is rotated through the operating string to which it is connected so that the cutter head advances into the formation, forming a cylindrical core which is received by the inner barrel 11. As the core passes into the inner barrel 11, the fluid, cuttings, and debris that may be trapped in the core barrel are forced upwardly through it. Upon the pressure in the upper end of the core barrel 11 becoming greater than the pressure on the circulation fluid, the valve member 22 is forced

open and the trapped fluid, cuttings, etc., pass upwardly through the opening 25. The valve member 22 is free to tilt or swing at will, and has considerable vertical movement so that a passage of large capacity is provided between it and the valve seat 26. The stop member 35 engages the shoulder 27 to limit upward movement of the valve member 22 and to positively prevent displacement of the valve member. Further, the arms 37 of the stop member operate to prevent the larger pieces of débris from entering the valve opening 25 and from becoming lodged between the valve member 22 and the seat 26. In this manner, fluid is permitted to freely pass out of the valve but any large objects that may be trapped in the inner barrel 11 are prevented from interfering with the action of the valve member 22.

After the core has been taken the valve member 22 is free to close. The valve member 22 is comparatively heavy and its lower face 29 is shaped so that it automatically falls to its proper central position in engagement with the seat 26 where it closes the inner barrel 11 against the downwardly flowing circulation fluid. It is to be noted that the valve means 12 embodied in the core drill does not involve any cages or other parts that are liable to catch or hold débris that may hold the valve open. The valve means therefore is particularly effective and dependable, and protects the core against the action of the circulation fluid.

The form of the valve means illustrated in Figs. 4 and 5 of the drawing embodies a modified type of strainer and a stop means 50. In this embodiment of the invention, the body 21^a and the valve member 22^a may be similar to or identical with the body 21 and the valve 22 described above. The valve member 22^a is provided at its lower end with a downwardly and inwardly tapering valve face 29^a adapted to cooperate with a seat 26^a at the upper end of the body to prevent the passage of circulation fluid downwardly into the body opening 24^a. A central stem 30^a projects downwardly from the lower end of the valve member 22 and extends below the shoulder 27^a when the valve is in the closed position.

The stop means and straining means 50 is integral with the stem 31^a. The means 50 includes a laterally or radially projecting offset stem portion 51 and a split or bifurcated stem portion 52. Before the valve member 22^a is assembled on the body 21^a, the bifurcated lower end portion 52 of the stem is bent downward from the offset por-

tion 51 as indicated by the broken lines in Fig. 4 of the drawing. When the lower bifurcated portion 52 of the stem is bent in this manner, it may be passed downwardly through the reduced portion 25^a of the body opening when the member 22^a is being arranged or assembled on the body opening. After the stem 30^a has been arranged within the body, the split lower end portion 52 of the stem is bent upwardly to the substantially horizontal position illustrated in the full lines in Fig. 4 of the drawing. The valve means is then ready for use, and the valve member 22 is positively held against displacement from the body 21^a.

The offset stem portion 51 and the ends of the arms A and B of the bifurcated part 52 are adapted to come into engagement with the shoulder 27^a during opening of the valve to limit upward movement of the valve member 22^a. The valve member 22^a is permitted to rotate or tilt at will, and operates in the same manner as the valve member 22 described above. The split portion 52 of the stem is operable to prevent any large objects from passing upwardly into the body opening where they might interfere with the operation of the valve member 22^a. The form of valve means illustrated in Figs. 4 and 5 of the drawing is particularly simple and inexpensive of manufacture and is very dependable and efficient in operation.

Having described only typical preferred forms of my invention, I do not wish to limit myself to the specific details set forth, but wish to reserve to myself any changes or variations that may appear to those skilled in the art or fall within the scope of the following claim.

Having described my invention, I claim:

In a core drill on the lower end of a drilling string, having a core receiving barrel open at its lower end, and valve means on the upper end of the barrel operable to prevent fluid from passing downwardly into the barrel and to permit fluid to pass upwardly out of the barrel, said means including a seat on the upper end of the barrel, a valve member cooperating with said seat to seal therewith, said valve member comprising a stem for guiding the valve member for limited vertical and lateral movement, and a seat in the top of the valve member for receiving a device of the character described lowered in the drilling string.

LEONARD BRADLEY.
